CCCLys.

UNITED STATES PATENT OFFICE.

LOUIS STOCKSTROM, OF ST. LOUIS, MISSOURI.

BOOK-SHELF.

SPECIFICATION forming part of Letters Patent No. 448,091, dated March 10, 1891.

Application filed April 15, 1890. Serial No. 348,030. (No model.)

To all whom it may concern:

Be it known that I, LOUIS STOCKSTROM, of the city of St. Louis, in the State of Missouri, have invented a certain new and useful Improvement in Book-Shelves, of which the following is a full, clear, and exact description, reference being had to the accompanying drawings, forming part of this specification.

My invention relates to certain improvements in that class of book-shelves which are provided with rollers on which the books rest; and my invention consists in features of novelty hereinafter fully described, and pointed out in the claims.

Figure I is an elevation illustrative of my invention. Fig. II is a horizontal section taken on line II II, Fig. I. Fig. III is a vertical section taken on line III III, Fig. II. Fig. IV is an enlarged detail section taken on line IV IV, Fig. II; and Fig. V is a similar view taken on line V V, Fig. II. Figs. VI and VII are detail sections.

Referring to the drawings, 1 represents the bottom, 2 the top, and 3 the vertical partitions, of a case particularly adapted to hold large books—such, for instance, as those used in the office of a recorder of deeds. Two of the books are shown at 4, Fig. I. If the case has only one row of shelves, 3 would represent the sides or ends of the case instead of partitions.

5 represents shelves upon which the books are supported. These shelves are composed of a horizontal series of rollers 6, (see Figs. II and III,) the rollers being journaled in strips 7, secured to the sides or partitions 3 of the case. The books are placed on the shelves, and the rollers turn as the books are shoved inwardly into the case. Broadly considered there is nothing new in forming shelves of such rollers.

Various means have been devised to prevent the edges of the books from binding on the sides of the cases or on the partitions 3 as they are shoved into and pulled out of the file, and one means which has heretofore been resorted to is to arrange vertical rollers against which the ends of the books would bear. To accomplish this same purpose, but more cheaply and with less expense of room, I form flanges 8 on the ends of the outer rollers 6 of each shelf, and the inner rollers of

each shelf may be provided with like flanges. The inner face of each flange is preferably made inclined, as shown at 9, Fig. V, so that 55 as the roller is turned by the inward or outward movement of the book the face of the flange does not rub the ends of the book, as only the base of each flange bears against the book, as shown at 9^a, Fig. I. By making the 60 flanges inclined the book is also more easily guided into its proper place when putting it on the shelf. I prefer to make a permanent or tight connection between the rollers and the flanges, so that the two will revolve together. By means of these flanges it will be seen that a rolling-surface will be presented to the ends of the book, as well as to the side of the book which rests upon the shelf composed of the rollers. 70

It is somewhat difficult to grasp these heavy books when they are in their inner position on the shelves, and as a means for starting their outward movement, so that they can be grasped by the hands, I have employed a bar 75 or rod 10 for each shelf. I have shown the inner ends of the bars turned upwardly and perforated to receive pins or stems 11, by which the inner ends of the bars are supported. (See Fig. III.) The inner ends of 80 the bars also extend upwardly beyond the pins 11, as shown at 12, so as to be above the lower faces of the books when in position, (see Fig. III,) and these extensions 12 may be faced with felt or other suitable material 13 85 to prevent rubbing the books. Near the outer end of each bar is an upright vertical extension 14, perforated to receive a pin 15, projecting inwardly from a strip 16, that extends across the case inside of the front roller. By 90 these pins 15 the outer ends of the bars or rods 10 are supported, and between the extensions or projections 14 and the bars 16 I prefer to place coil-springs 17, the tendency of which is to hold the bars 10 in their inner position. The extreme outer end of each bar is preferably turned upwardly and is provided with a hand-hold or hook 18, which fits, when the bar is in its inner position, between the inner ends of the outer roll 6, (the outer roll 6 being divided for the purpose of admitting this hand-hold to move inwardly into line with the face of the outer roller, so that the case would not be disfigured by the hand- 100

holds projecting beyond the rollers, or, in other words, beyond the outer edges of the shelves composed of the rollers.) By grasping the hand-hold 18 and pulling the bar 10 outwardly from the position shown on the second shelf from the top of Fig. III to the position shown upon the bottom shelf in Fig. III the books are pulled out sufficiently by this means to permit them to be easily grasped by the hand and withdrawn from the case. As soon as the handle 18 is released the bar 10 is thrust to its inner position by the spring 17 out of the way.

To prevent books coming in contact with the springs 17 or the uprights or projections 14, I prefer to locate guards 20 over these parts, as shown in Figs. II and III.

To afford additional rigidity to the partitions 3, I bind their outer edges by means of a strip 20^a, as shown in Fig. VI, and after it is applied I corrugate the strips, together with the edges of the partitions, as shown in Fig. VII, thus holding the binding on the partitions and affording greater strength to the partitions at small expense.

I claim as my invention—

1. A book-case having shelves provided with rollers, one or more of said rollers having flanges at the ends, substantially as and for the purpose set forth.

2. A book-case having roller-shelves, one or more of the rollers of which have inclined

flanges at the ends, substantially as and for the purpose set forth.

3. A book-case having roller-shelves and a pull-bar or rod 10, in connection with a shelf having an upturned inner end, substantially as and for the purpose set forth.

4. A book-case having roller-shelves and a spring pull-bar or rod 10, in connection with a shelf having an upturned inner end, substantially as and for the purpose set forth.

5. A book-case having roller-shelves and a pull-bar or rod, in connection with a shelf having perforated upturned inner ends and extension-pins passing through the perforations, and a spring 17, substantially as and for the purpose set forth.

6. In a book-case, the combination of the roller-shelves, pull-bars having handles 18, adapted to fit between the inner ends of the sectional outer rollers, and springs for holding the bars in their inner positions, substantially as and for the purpose set forth.

7. In a book-case having roller-shelves, the combination of pull-bars by which the books are withdrawn and the shields 20 over the pull-bars between the front rollers of the shelves, substantially as and for the purpose set forth.

LOUIS STOCKSTROM.
